(57) **CLAIM**

The ornamental design for a wireless speaker, as shown and described.

DESCRIPTION

FIG. 1 is a front perspective view of a wireless speaker, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view showing the wireless speaker in an open state thereof; and,

FIG. 10 is a rear perspective view showing the wireless speaker in an open state.

The broken lines in the drawings illustrate the portions of the wireless speaker, which form no part of the claimed design.
